UNITED STATES PATENT OFFICE.

AMBROSE INEMER AND PATRICK LYSTON, OF BALTIMORE, MARYLAND.

CAR-AXLE BOX AND LUBRICATOR.

SPECIFICATION forming part of Letters Patent No. 413,066, dated October 15, 1889.

Application filed August 6, 1889. Serial No. 319,911. (No model.)

To all whom it may concern.

Be it known that we, AMBROSE INEMER and PATRICK LYSTON, citizens of the United States, residing at Baltimore, in the State of Maryland, have invented certain new and useful Improvements in Car-Axle Boxes and Lubricators, of which the following is a specification.

This invention relates to an improved car-axle box and journal lubricator, and is illustrated in the accompanying drawings, in which—

Figure 1 is a section of the car-axle box and shows the journal and lubricator. Fig. 2 is a part front end elevation and section of the car-axle box. Fig. 3 shows two views of the oil-dipper.

The box A has vertical sides b, horizontal top c, and sloping bottom d, which inclines toward the front end e, where it is lowest. At the front the box has a circular head A', and a narrow circular chamber f is thereby formed. The lid or cover g comprises a portion of the said circular chamber, and is attached by hinges h, as usual. The lowermost part f' of the circular chamber f projects a little below the front end e of the bottom and serves as a receptacle for the collection of oil that drains down from the journal I. The brass bearing J over the journal may be of any desired construction. In the present instance it has at the front end a reception-lip k, which projects a little, and this lip forms a shallow recess l. A longitudinal groove m extends across the top of the brass, and one or two ducts n pass down from said groove.

An arm O is secured to the end of the axle-journal I in any suitable or convenient manner. In the present instance a screw p is employed to secure the arm. When the car is in motion and the axle revolves, the arm will turn like a crank-arm, and its path of rotation will be in the circular chamber f' at the front of the box. The arm at its extremity has a small dipper q, of any suitable shape. The dipper projects at both sides of the arm,

so as to serve equally well when turned either way. The small dipper q at each revolution passes through the lowermost part f' of the circular chamber, and one of its sides will 50 take up a small quantity of oil, which will be carried to the topmost part of the chamber, where it will drip from the dipper, and some of it will pass onto the reception-lip k of the brass. This oil will enter the recess l, and 55 then pass into the groove m, and from there down the ducts n to the journal I. All excess of oil from the journal will drain down the inclined bottom d into the lowermost part f' of the circular chamber. The box may be 60 packed with waste or other material.

It will be seen that mechanical provision is here made for taking oil from the bottom of the box and applying it to the top of the journal.

In the present instance the dipper-arm is 65 shown applied to a car-axle; but it may be applied to other things, such as shafts.

It is obvious some changes in the construction of the box may be made without affecting the scope of the patent that may be 70 granted for this invention.

Having described our invention, we claim—

The combination of the box having a bottom which inclines toward the front, a circular head at the front of the box, the lowermost part of which projects below the box-bottom and forms a receptacle f', an axle or shaft, a bearing J, having a projecting oil-lip, a longitudinal groove m, extending therefrom across the top of the bearing, a duct passing 75 down from said groove, and an arm secured to the axle and having at its extremity a dipper which projects at both sides of the arm.

In testimony whereof we affix our signatures in the presence of witnesses.

AMBROSE INEMER.
PATRICK LYSTON.
